UNITED STATES PATENT OFFICE

ROBERT L. CALLAHAN, OF LOUISVILLE, KENTUCKY.

MEANS FOR FASTENING SACKS.

1,242,139.

Specification of Letters Patent.

Patented Oct. 9, 1917.

Application filed August 20, 1915. Serial No. 46,403.

To all whom it may concern:

Be it known that I, ROBERT L. CALLAHAN, a citizen of the United States, residing at Louisville, in the county of Jefferson and 5 State of Kentucky, have invented certain new and useful Improvements in Means for Fastening Sacks, of which the following is a specification.

My invention relates to means for fastening sacks after the same have been filled with grain, flour or other substances. It is the object of my invention to provide fastener mechanism which may easily be applied to the open corners of sacks which have 10 previously been sewed across the top so as to leave only comparatively small openings at the corners. My invention provides means for quickly and securely closing these openings, and at the same time forming ears 15 for the handling of the sack, by merely slipping said means down over the corner which is gathered together adjacent said opening. Various types of devices may be employed for this purpose but comprise primarily a 20 ring with an opening in the center, said opening being so formed or having its edges so formed as to adapt the ring to be slid in one direction along the gathered sack corner and to restrain movement of the ring 25 in the opposite direction, and also to hold the ring in its inward position on the gathered sack corner where said corner is clamped together by the ring so as to effectively close the opening.

30 The full objects and advantages of my invention will appear in connection with the detailed description thereof and are particularly pointed out in the claims.

In the drawings, illustrating the application of my invention in one form,—

Figure 1 is an elevational view of a sack being filled. Fig. 2 is an elevational view of a filled and sealed sack. Fig. 3 is a plan view of the stock out of which my fastener 40 is made. Fig. 4 is a plan view of a finished fastener drawn to full scale. Fig. 5 is an elevational sectional view of the fastener shown in Fig. 4, and Fig. 6 is a full size detail of a corner of a sack sealed with my 45 novel fastener. Fig. 7 is an elevational view of a slight modification of the fastener shown in Figs. 4 and 5. Fig. 8 is a perspective view of another modification of the same, and Figs. 9 and 10 are plan and elevational views, respectively, of a third modification of the same.

The sacks 10 may be of any desired size or shape and constructed of any fabric material commonly used for sacks, such as jute, burlap or cotton bagging. Such sacks 60 formed in the ordinary manner are partially closed across the top, as indicated at 14, leaving openings 15 at each side of the closed portion, or in the upper corners 16 of the sacks, which openings are adapted to receive filling spouts 17 through which the grain, flour, lime, cement, salt, sugar or other material which it is desired to inclose within the sacks may be introduced. The filling of the sacks 10 may be accomplished 65 in any well-known manner or by means of a special process and apparatus devised by me and for which protection will be sought in another application.

After the same has been filled with the 70 requisite quantity of material the corners of the sack are gathered together so as to form ears and such gathered corners are inserted through a circular fastener member 18, a preferred form of which is shown in 75 Figs. 3 to 7, inclusive. Such a fastener member is primarily formed of a circular disk of metal having transverse slits 19 cut in the same, as indicated in Fig. 3, the intervening material being pressed up to 80 form inwardly-projecting pointed tongues 20 surrounding a central opening 23. A flat portion 21 of the disk may be provided with a flange 22 to increase the strength of the 85 same and the fastener may be cut, as shown 90 in Fig. 7, so as to form small pointed tongues 24 at the base of the longer tongues 20. Other forms of fastener devices of a 95 generally similar nature may be employed, such as those shown in Fig. 8 and Figs. 9 and 10. In each case there would be provided a closed ring with a central opening 100 provided with some form of sack engaging member. As in Fig. 8, a disk of metal is formed with an elongated pointed opening 26, having preferably toothed walls 27 and 105 28, the acute angles of the ends of the opening 26 providing means for holding the fabric of the sack by wedging the same therein while the teeth will hold the sack by engagement within the body of the fabric. In Figs. 9 and 10 is shown a fastener made of twisted wire comprising a ring 30 formed of the untwisted portions of the wire and prongs 31 formed from loops 110 of said wire set up from the ring and cut across. The jagged free ends of wire thus

formed are turned inwardly and engage the body of the sack to hold the ring in place. Whichever form of fastener is employed, the same will be applied to the sacks after 5 filling in the same way, that is, the corners of the sacks will be gathered together to form ears 32 and the fastener member 18 is slipped over the gathered ear and pressed with the hand tightly down upon the body 10 of grain at the base of the ear. This results in compacting the ear so as to completely close the opening into the sack and the fastener remains in position because of the engagement with the fabric of the ears 15 of the prongs and angles formed around the opening in the fastener.

The advantages of my invention will be apparent. No sewing or tying of the sack after filling is required. The double opening 20 on each side of the sack permits ready filling, and the application of the fasteners to the ears in the manner described not only closes these openings but also provides the ears for handling the sacks. It will further 25 be apparent that the fasteners may be applied with the utmost ease and despatch, and may readily be removed by turning back the prongs or edges with a knife or bar, or by cutting the fastener with a shear or other 30 wire or metal-cutting instrument.

I claim:

1. A sack mouth fastener comprising a body portion formed with an opening therein adapted to surround a portion of the sack 35 gathered and close the sack mouth, and a plurality of prongs extending inwardly from the margin of said opening in close proximity to each other and adapted to engage the fabric of the gathered sack portion 40 to hold the fastener in position thereon.

2. A sack mouth fastener comprising a discoidal body portion having an opening therein, and means issuing from the walls of said opening for holding said body in place 45 upon a gathered portion of a sack to close the same.

3. A sack mouth fastener formed of sheet metal comprising a flat circular body por-

tion and a plurality of prongs pressed outward from the central portion of the disk 50 to form a central opening for permitting the disk to be drawn over a gathered portion of a sack to close the same, said prongs holding the fastener in place thereon.

4. A sack fastener formed of sheet metal 55 comprising a flat circular body portion, a plurality of prongs formed from the central portion of said disk by cutting the disk on radial lines and pressing out the ears thus formed substantially at right angles to the 60 remainder of the disk, thus forming a central opening through which a gathered portion of a sack may be passed to close the same, said ears holding the fastener in place.

5. A sack mouth fastener formed of sheet metal 65 comprising a flanged body portion having an opening therein and adapted to be drawn over a gathered portion of a sack to close the same, a turned-over edge on the periphery of said flanged body portion for 70 stiffening the same and presenting a smooth surface to be grasped in applying the fastener to the sack, and means for holding the fastener in place upon the gathered portion of said sack.

6. A sack-mouth fastener comprising a body portion formed with an opening therein adapted to surround a portion of the sack gathered about the sack mouth, and a plurality of prongs extending from the margin of 80 the opening inwardly, said prongs being formed with pointed ends and flaring edges meeting in acute angles at the margin of said opening.

7. A sack mouth fastener comprising a 85 body portion having an opening therein provided with a continuous wall, and means issuing from said wall for holding said body in place upon a gathered portion of a sack 90 to close the same.

In testimony whereof I affix my signature in presence of two witnesses.

ROBERT L. CALLAHAN.
